UNITED STATES PATENT OFFICE.

LOUIS T. BULLEY, OF NEW HAVEN, CONNECTICUT, ASSIGNOR TO C. COWLES & COMPANY, OF NEW HAVEN, CONNECTICUT, A CORPORATION OF CONNECTICUT.

WINDOW REGULATOR.

Application filed July 16, 1920. Serial No. 396,790.

To all whom it may concern:

Be it known that I, Louis T. BULLEY, a citizen of the United States, residing at New Haven, county of New Haven, State of Connecticut, have invented an Improvement in Window Regulators, of which the following is a specification.

This invention relates to window regulating mechanism and has particular reference to mechanism for manipulating sliding disappearing windows, doors, and the like, such for example, as are used on automobile and railway cars, and the invention has for its general object to furnish improved mechanism of the present character. To this end I provide a window regulator of simplified and durable construction which may be manufactured with but a minimum of expense for the reason that nearly all of the parts may be composed of pressed metal.

A specific object is to provide improved means of the general type disclosed in Patent No. 1,245,189, granted to me on November 6, 1917, for producing lateral movement of the window to cause it to automatically latch itself in closing and to automatically unlatch itself in opening. Another specific object means for yieldingly holding one of the sprockets against the continuous lifting chain of the invention whereby the chain is properly tensioned to efficiently perform its function. Still further specific objects are to provide cushioning means whereby the window is prevented from locking with a bang when raised, to provide adjusting means for regulating the spring action of the sprockets to provide simple and readily accessible means for disconnecting the window from the operating mechanism whenever this is desirable, and to provide adequate antirattling means for the control mechanism of the window regulating mechanism of the invention.

With the above and other objects in view, the invention comprises the construction, arrangement and combination of parts as now to be fully described and hereinafter specifically claimed.

In the accompanying drawing forming a part of this specification,

Fig. 1, an elevation of a window and

frame, showing the window lift mechanism of the invention;

Fig. 2 a vertical, sectional view taken substantially through the center of Fig. 1;

Fig. 3 a detail elevation of the window lift mechanism on an enlarged scale;

Fig. 4 an elevation as seen from the right in Fig. 3;

Fig. 5 a detail, central, sectional view of the operating handle and control mechanism;

Fig. 6 a section on line 7—7 in Fig. 5;

Fig. 7 a section as on line 8—8 in Fig. 5;

Fig. 8 a section on line 9—9 in Fig. 7;

Fig. 9 an enlarged detail view of one of the sprockets and the spring drum;

Fig. 10 a section on line 11—11 in Fig. 9;

Fig. 11 a view on line 12—12 in Fig. 5, the cover being removed;

Fig. 12 a detail sectional view of the spring drum adjusting button; and

Fig. 13 is a section on line 14—14 in Fig. 6.

Referring to the drawing, 21 denotes a frame with a window therein. The frame is provided with a pair of opposite channel guides 22 pivoted at their tops to the frame as indicated at 23. 24 denotes a sliding sash, herein shown as a pane of glass provided with a bottom beading 25 having a catch 26 which is adapted to engage a latch 27 carried by the frame sill member denoted by 28. Mounted on the other sill member, denoted by 29, is a plate 30 which is adapted to support the operating handle and the control mechanism, a part of the control mechanism being located in sill member 29 and a part projecting outwardly beyond said sill member as more clearly shown in Fig. 2.

Referring now more particularly to Figs. 5, 6, 11 and 13, a cup shaped member 31 doweled into plate 30 as indicated at 32 and secured to said plate by means of rivets 33 provides a housing for the part of the control mechanism extending beyond plate 30. Rivets 33 also secure a ratchet 34 provided with ratchet teeth 35 to said cup. A hub 36 located in the cup and ratchet and resting against plate 30 rotatably receives the main shaft, denoted by 37 which passes through plate 30 and by means of which rotary

movement is imparted to the part of the control mechanism projecting outwardly from the sill member. The inner end of the main shaft, as clearly shown in Fig. 11, is rigidly secured, as indicated at 38 to a gear 39. A cover 40 is provided for gear 39, and rotatably mounted in the cover, as indicated at 41 in Fig. 5, is a short shaft 42 the outer end of which is squared to rigidly carry a pinion 43, which, as disclosed in Fig. 11, is adapted to mesh with gear 39. The cover supports a bracket 44 provided with a circular opening which rotatably receives the hub, denoted by 45, of an operating handle 46, the inner squared end of the short shaft, denoted by 47, being socketed into the hub and a screw 48 in the hub and shaft insuring the position of the hub on the shaft. A flat spring 49 secured to the cover at 50 and bearing against the pinion and the squared portion of the short shaft as indicated at 51 provides antirattling means for the gear and pinion as will be understood. 52 denotes a disk which is loosely mounted on hub 36 and positioned in the cup shaped member just beyond the ratchet. This disk is provided with pawls 53 having inwardly extending lugs 54 which pass through a cut away portion of the disk denoted 55 and are adapted to engage the teeth of the ratchet. Encircling the cup shaped member is a sprocket consisting of two pressed metal members denoted by 56 and 57, respectively, which are secured to each other as indicated at 58, and the outer periphery of the cup shaped member is recessed as shown at 59 to provide, together with the two members of the sprocket, a race way for balls 60 for an obvious purpose. Member 56 of the sprocket terminates short of the base of the cup member as clearly shown, and member 57 provides a cover plate for the portion of the mechanism located in the cup shaped member. Pins 61 embedded in disk 52 and sprocket member 57 and each provided with an enlarged portion 62 for a purpose to be explained, are adapted to connect said disk and sprocket and space them from each other. 63 denotes a longitudinally movable pawl tripping plate which is provided with a relatively large opening 64 and with radial slots 65, the opening being adapted to receive the head, denoted by 66, of the main shaft, and the radial slots adapted to slidably receive the enlarged portions of pins 61 whereby longitudinal movement of the tripping plate is limited. The head of the main shaft, as more clearly shown in Fig. 6, is preferably integral with said shaft and is provided with oppositely extending arms 67 which are adapted to engage shoulders 71 in the tripping plate in a manner presently to be described. Pawls 53 are pivoted to disk 52 at approximately their mid-length and the tail of each pawl is engaged by one arm of a spring 68. The springs are coiled at their midlengths about pins 69 extending from the disk, and the opposite end of each spring bears against the wall of a depression 70 in the pawl tripping plate to normally hold said tripping plate in its inoperative position and the pawls in operative engagement with the teeth of the ratchet. When now the operating handle is turned in either direction, it will be apparent that pinion 43 will cause gear 39 and the main shaft to be rotated. The first effect of rotation of the main shaft will cause one of arms 67 to engage one of shoulders 71 and raise the tripping plate from its inoperative position as shown in Fig. 6 to lift the pawls from the ratchet teeth, and the tripping plate will remain in its operative position so long as the main shaft is being rotated, the relative sizes of opening 64 and the head 85 of the main shaft being such that the oppositely extending arms can not completely turn over in said opening. Continued rotation of the main shaft will rotate the sprocket, the force being applied through the tripping plate and pins 61, as will be obvious. The instant the operating handle is released, springs 68 will return the tripping plate to its inoperative position and will cause the pawls to engage opposite sides 95 in any desired position.

72 denotes a horizontally disposed frame member secured to the lower portion of the window frame as indicated at 73, and 74 denotes an upright frame member which extends between plate 30 and frame member 72, the upright frame member being secured to plate 30 as indicated at 75 and to frame member 72 as indicated at 76.

A carrying plate 77 is for the purpose of supporting a drum 78 and a larger sprocket 79, which, together with the sprocket hereinbefore described, carries the continuous window lifting chain denoted by 80. As more clearly disclosed in Fig. 10, a headed screw 81 passes through said plate, drum and sprocket and is provided with a locking nut 82 which holds these parts to each other. 83 denotes a flat spiral spring one end of 115 which is secured to the drum as indicated at 84 and the other end of which is secured to the larger sprocket as indicated at 85, and the drum and sprocket are arranged with respect to each other to provide a race way 120 for balls 86. The larger sprocket is adapted to turn on screw 81 as a pivot point and the drum is adapted to be adjustably and fixedly secured to the carrying plate so that the flat spiral spring winds and unwinds as the 125 sprocket is turned on its axis, the arrangement here being for the spring to wind as the window is being lowered, that is, opened. 87 denotes a housing for the flat spiral spring. The adjustment between the drum 130

and the carrying plate therefor is for the purpose of regulating the spring action of the larger sprocket, as will be understood. The carrying plate is recessed to receive a short tubular member 88 in which is positioned a spring pressed pin 89 provided with a collar 90, and the drum is provided with a series of perforations 91 adapted to receive the pin, the collar, as will be obvious from Fig. 12, being for the purpose of limiting the inward movement of the pin. Screw 81 is provided with a squared portion 92 which is arranged to engage a corresponding opening in the drum, and the end of the screw which extends beyond the locking nut is also squared as shown at 93. To revolve the drum to regulate the spring action of the flat spiral spring, all that is necessary is to pull on the spring pressed pin until it is released from the drum to then cause squared end 93 of screw 81 to be turned in the desired direction, and to then release the pin so that it enters one of the perforations in the drum, it being understood that the larger sprocket will be held in stationary position by the continuous lifting chain while the adjustment is being made.

Carrying plate 77 is eccentrically pivoted to the upright frame member as indicated at 94. A hook bracket 95 carried by said upright member has secured to it one end 96 of a coil spring the other end of which is attached to the carrying plate as indicated at 97. It will be apparent that the coil spring is for the purpose of causing the larger sprocket to be yieldingly held against the continuous lifting chain to cause the chain to be at all times under the proper tension for its purpose. Pins 98 extending from the frame members and engaging arcuate slots 99 in the carrying plate are for the purpose of limiting the movement of the carrying plate.

The bottom beading of the sliding sash has secured to it a window carrying plate 100 which in turn is adapted to be detachably connected to a plate 101 supported from the continuous lifting chain. As shown more clearly in Figs. 7 and 8, plate 101 is provided with bayonet slots 102 and with a straight slot 103 which is positioned between the bayonet slots, and the window carrying plate is provided with forwardly projecting pins 104 adapted to enter the bayonet slots and a locking lever 105 mounted in the window carrying plate is provided with an eccentrically positioned pin 106 adapted to enter the straight slot in plate 101. Lugs 107 are for the purpose of limiting the downward movement of the locking lever. It will be evident that to fasten the window carrying plate to plate 101, pins 104 are first passed into the bayonet slots and the locking lever is next moved to the position in which it is shown in Fig. 7, the eccentrically arranged

pin, in the meantime, causing pins 104 to move into the offset portions of the bayonet slots. To disconnect the plates, the lever is swung in clockwise direction from the position shown in Fig. 7, as will be understood.

Plate 101 is provided with an elongated slot 108 for the purpose now to be explained. A sliding block 109 arranged on one side of the elongated slot is riveted to a tubular cam 110, arranged on the opposite side of said slot, the block and tubular cam being movable as a unit longitudinally of said slot. A preferably triangular plate 111 securely fixed to one of the links of the continuous lifting chain, as denoted at 112, has rigidly secured thereto and projecting therefrom a relatively large pin 113 which passes through a hole in the sliding block and enters the tubular cam as more clearly shown in Fig. 8. A relatively small pin 114 adapted to travel in a cam slot 115 in the tubular cam is fixedly secured to the relatively large pin as more clearly disclosed at 116 in Fig. 8. 117 denotes a closure cap in the tubular cam. When now the window lifting chain is caused to be moved in the direction of the arrow in Fig. 7, and the portion of the chain which carries the triangular plate commences to move from right to left in said figure, it will be obvious that the relatively large pin will be caused to turn in a counter-clockwise direction. This turning movement of the relatively large pin will force the relatively small pin to ride in the cam slot, which, as suggested in Figs. 4 and 8, is of a configuration to cause plate 101 to move outwardly on the relatively large pin. This outward movement will continue until the triangular plate and consequently the sash has reached its highest elevation, and the catch carried by the beading is positioned directly over the latch carried by one of the sills. As the triangular plate moves from its highest elevation to the position shown in Fig. 7, the sash will be lowered so that the catch will engage the latch as it is shown in Fig. 8, the portion of the cam slot through which the relatively small pin passes during this movement being straight. When the lifting chain is moved in the opposite direction to lower the window, the catch will first be lifted from the latch and the cam slot will cause plate 101 to move inwardly on the relatively large pin, as will be obvious.

Plate 101 is provided with a second elongated slot 118 which is parallel with elongated slot 108. Slidably arranged in the second elongated slot is a cushion block 119 provided with a shoulder portion 120. A spring 121 secured to the cushion block as indicated at 122 and to plate 101 as indicated at 123 normally holds the cushion block in the right hand end of the second

elongated slot as it is shown in Fig. 3. The sliding block in elongated slot 108 is provided with a shoulder portion 124 adapted to bear against the shoulder portion of the cushion block when said sliding block moves from right to left as suggested in Figs. 3 and 7. It will be apparent that the cushion block is moved from right to left against the action of spring 121, and provides means for preventing the sliding sash from locking with a bang when raised. It will further be apparent that the cushion block will assist the sliding block in its movement toward the right from the position shown in Fig. 7 when it is desired to release the catch from the latch to lower the sliding sash.

Assuming that the sliding sash is in its raised position and the window is closed, all that is necessary to lower the sash to open the window is to turn the operating handle in a counter-clockwise direction. This causes the gear which meshes with the pinion actuated by the operating handle, as well as the main shaft and the control mechanism, to be rotated in a clockwise direction. To elevate the sliding sash, the operating handle is turned clockwise.

What I claim is:

1. In a control mechanism of the class described a main shaft by which the control mechanism is actuated, a gear rigidly secured to the main shaft, a pinion adapted to mesh with the gear, a short shaft by which the pinion is carried, an antirattling spring bearing against the short shaft and pinion, and an operating handle for rotating the short shaft.

2. In a control mechanism of the class described a main shaft by which the control mechanism is actuated, a gear rigidly secured to the main shaft, a pinion adapted to mesh with the gear, a short shaft by which the pinion is carried, a cover for the gear and pinion, an antirattling spring secured to the cover and bearing against the pinion and short shaft, and an operating handle for rotating the short shaft.

3. In a mechanism of the character described, a window carrying plate provided with a slot, a sliding block arranged in said slot, and a tubular cam riveted to said block and provided with a cam slot, said block and tubular cam arranged on opposite sides of said plate, in combination with a lifting chain, a plate secured thereto, a relatively large pin rigidly carried by said last mentioned plate and adapted to pass through said block and slot and to enter said tubular cam, and a relatively small pin rigidly secured to the relatively large pin and adapted to ride in said cam slot.

4. In a mechanism of the character described, a window carrying plate provided with a slot, a sliding block arranged in said

slot, and a tubular cam riveted to said block and provided with a cam slot, said block and tubular cam arranged on opposite sides of said plate and adapted to travel in unison, in combination with a lifting chain, a preferably triangular plate secured thereto, a relatively large pin rigidly carried by said triangular plate and adapted to pass through said block and slot and to enter said tubular cam, and a relatively small pin rigidly secured to the relatively large pin and adapted to ride in said cam slot.

5. In a mechanism of the character described, a window carrying plate provided with a slot, a sliding block arranged in said slot, and a tubular cam riveted to said block and provided with a cam slot, said block and tubular cam arranged on opposite sides of said plate and adapted to travel in unison in said slot, in combination with a pair of sprockets, a continuous lifting chain, carried thereby, a preferably triangular plate secured to said lifting chain, a relatively large pin rigidly carried by said triangular plate and adapted to enter said tubular cam, and a relatively small pin secured to the relatively large pin and adapted to ride in said slot, whereby when said lifting chain is elevated and said triangular plate is moved transversely of said sprockets, the relatively large pin is turned to force the relatively small pin to ride in the cam slot and thereby cause the window lifting plate to move outwardly on the relatively large pin for the purpose specified.

6. In a mechanism of the character described, a window carrying plate provided with a slot, a sliding block arranged in said slot, and a tubular cam secured to said block and provided with a cam slot, said block and tubular cam arranged on opposite sides of said window carrying plate, in combination with a pair of sprockets and means for causing one of said sprockets to be rotated, a continuous lifting chain carried by said sprockets and adapted to be actuated thereby, a preferably triangular plate secured to the lifting chain, a relatively large pin rigidly carried by said triangular plate and passing through said sliding block and entering said tubular cam, and a relatively small pin secured to said relatively large pin and adapted to ride in said cam slot.

7. In a mechanism of the character described, a window carrying plate provided with a slot, a sliding block arranged in said slot, and a tubular cam secured to said block and provided with a cam slot, said block and tubular cam arranged on opposite sides of said window carrying plate, in combination with a pair of sprockets and means for causing one of said sprockets to be rotated, a continuous lifting chain carried by said sprockets and adapted to be actuated

- thereby, a relatively large pin supported from said continuous lifting chain and adapted to be given a turn when said chain is moved to a position so that said relatively large pin travels transversely of said sprockets, and a relatively small pin secured to said relatively large pin and adapted to ride in said cam slot to cause said window carrying plate to move longitudinally of said relatively large pin.
8. In a mechanism of the character described, a window carrying plate provided with a slot, a sliding block arranged in said slot, and a tubular cam secured to said sliding block and provided with a cam slot, said block and tubular cam arranged on opposite sides of said window carrying plate, in combination with a lifting chain, a relatively large pin supported from said lifting chain and adapted to be given a turn by said chain, and a relatively small pin secured to said relatively large pin and adapted to ride in said cam slot, whereby said window carrying plate is adapted to move longitudinally of said relatively large pin.
9. In a mechanism of the character described, a window carrying plate provided with a slot, a sliding block arranged in said slot and provided with an opening, and a tubular cam secured to said sliding block and provided with a cam slot, said block and tubular cam arranged on opposite sides of said window carrying plate, in combination with a lifting chain, a relatively large pin supported from the lifting chain and passing through the opening in the sliding block and adapted to be given a turn in either direction by said chain, and a relatively small pin secured to said relatively large pin and adapted to ride in said cam slot to cause said window carrying plate to move longitudinally of said relatively large pin.
10. In a mechanism of the character described, a window carrying plate provided with a slot, a sliding block arranged in said slot, and a tubular cam secured to said sliding block and provided with a cam slot, in combination with a lifting chain, a relatively large pin supported therefrom, and a relatively small pin secured to said relatively large pin and adapted to ride in said cam slot.
11. In a mechanism of the character described, a window carrying plate provided with a pair of longitudinal slots, a sliding block arranged in one of said slots and a tubular cam secured to said sliding block and provided with a cam slot, a cushion block arranged in the other of said slots and a spring by which said cushion block is tensioned, said sliding block and cushion block provided with corresponding shoulders adapted to engage each other, in combination with a lifting chain, a relatively large pin supported therefrom, and a relatively small pin secured to said relatively large pin and adapted to ride in said cam slot to cause said window carrying plate to move longitudinally of said relatively large pin.
12. In a mechanism of the character described, a window carrying plate provided with a pair of longitudinal slots, a sliding block arranged in one of said slots and a tubular cam secured to said sliding block and provided with a cam slot, a cushion block arranged in the other of said slots and a spring by which said cushion block is tensioned, said sliding block and cushion block provided with corresponding shoulders adapted to engage each other, in combination with a lifting chain, a relatively large pin supported from the lifting chain and adapted to be given a turn in either direction by said chain, and a relatively small pin secured to said relatively large pin and adapted to ride in said cam slot to cause said window carrying plate to move longitudinally of said relatively large pin.
13. In a mechanism of the character described, a window carrying plate provided with a pair of parallel slots, a sliding block arranged in one of said slots and a tubular cam secured to said sliding block and provided with a cam slot, and cushioning means arranged to slide in the other of said slots, said sliding block and cushioning means provided with corresponding shoulders, in combination with a pair of sprockets and means for causing one of said sprockets to be rotated, a continuous lifting chain carried by said sprockets and adapted to be actuated thereby, a relatively large pin supported from said continuous lifting chain and adapted to be given a turn when said chain is moved to a position so that said relatively large pin travels transversely of said sprockets, and a relatively small pin secured to said relatively large pin and adapted to ride in said cam slot to cause said window carrying plate to move longitudinally of said relatively large pin, and said shoulder on said sliding block adapted to bear against said shoulder on said cushioning means while said relatively large pin is moving transversely of said sprockets.
14. In a mechanism of the character described, a window sill provided with a latch, a sliding sash provided with a catch, a carrying plate secured to the sliding sash and provided with a slot, a sliding block and a tubular cam arranged in said slot, said tubular cam provided with a cam slot, in combination with a lifting chain, a relatively large pin supported therefrom, and a relatively small pin imbedded in the relatively large pin and adapted to ride in the cam slot, whereby said carrying plate is movable longitudinally on said relatively large pin to cause said catch to engage said latch or to be released therefrom.
15. In a mechanism of the character de-

- scribed, a window sill provided with a latch, a sliding sash provided with a catch, a carrying plate secured to the sliding sash and provided with a slot, a sliding block arranged in said slot, a tubular cam secured to said sliding block and provided with a cam slot, said block and tubular cam arranged on opposite sides of said carrying plates, in combination with a lifting chain, a relatively large pin supported therefrom and adapted to pass through the sliding block and adapted the tubular cam, and a relatively small pin secured to the relatively large pin and adapted to ride in the cam slot, whereby said carrying plate is movable longitudinally on said relatively large pin to cause said catch to engage said latch or to be released therefrom.
16. In a mechanism of the character described, a window sill provided with a latch, a sliding sash provided with a catch, a carrying plate secured to the sliding sash and provided with a slot, a sliding block arranged in said slot, a tubular cam secured to said sliding block and provided with a cam slot, said block and tubular cam arranged on opposite sides of said carrying plate, in combination with a pair of sprockets and means for causing one of said sprockets to be rotated, a continuous lifting chain carried by said sprockets and adapted to be actuated thereby, a preferably triangular plate secured to the lifting chain, a relatively large pin rigidly carried by said triangular plate and passing through said sliding block and entering said tubular cam, and a relatively small pin secured to said relatively large pin and adapted to ride in said cam slot.
17. In a mechanism of the character described, a window sill provided with a latch, a sliding sash provided with a catch, a carrying plate secured to the sliding sash and provided with a slot, a sliding block arranged in said slot, a tubular cam secured to said sliding block and provided with a cam slot, said block and tubular cam arranged on opposite sides of said carrying plate, in combination with a pair of sprockets and means for causing one of said sprockets to be rotated, a continuous lifting chain carried by said sprockets and adapted to be actuated thereby, a relatively large pin supported from said continuous lifting chain and adapted to be given a turn when said chain is moved to a position so that said relatively large pin travels transversely of said sprockets, and a relatively small pin secured to said relatively large pin and adapted to ride in said cam slot to cause said window carrying plate to move longitudinally of said relatively large pin, whereby said catch may be made to engage said latch or to be released therefrom.
18. In a mechanism of the character described, a pair of sprockets one of which is mounted on an eccentrically pivoted support, a continuous lifting chain carried by said sprockets, and means associated with said eccentrically pivoted support whereby said sprocket may be yieldingly held against said chain.
19. In a mechanism of the character described, a pair of sprockets one of which is mounted on an eccentrically pivoted support, a continuous lifting chain carried by said sprockets, and means associated with said eccentrically pivoted support whereby said sprocket may be yieldingly held against said chain, said means comprising a spring secured to a support and to said eccentrically pivoted support.
20. In a mechanism of the character described, a carrying plate, a drum and a sprocket, means for holding said drum and sprocket to each other and to the carrying plate, a spiral spring arranged between said drum and sprocket and having its opposite ends connected to said drum and sprocket, respectively, and means whereby said drum may be adjustably secured to said carrying plate comprising a series of openings in one of said members and a pin slidably mounted in the other member and adapted to cooperate with said openings to hold the drum in adjusted position.
21. In a mechanism of the character described, a carrying plate, a drum and a sprocket rotatably secured thereto and adapted to rotate with respect to each other, a spiral spring arranged between said drum and sprocket and adapted to supply said sprocket with a spring action, and means for adjustably securing said drum to said carrying plate, said means comprising a spring pressed pin arranged in said plate and adapted to enter any one of a number of perforations in said drum.
22. In a mechanism of the character described, a window carrying plate and a plate detachably secured thereto, one of said plates provided with bayonet slots and with a straight slot between the bayonet slots, and the other of said plates provided with pins adapted to engage the bayonet slots and with a locking lever equipped with an eccentrically positioned pin adapted to enter said straight slot.

In testimony whereof I affix my signature.

LOUIS T. BULLEY.
